UNITED STATES PATENT OFFICE.

LESLIE EARL SEBALD, OF RIDGEWOOD, NEW JERSEY, ASSIGNOR TO THE GRISCOM-RUSSELL COMPANY, OF NEW YORK, N. Y., A CORPORATION OF DELAWARE.

LOW-HEAT-LEVEL EVAPORATOR SYSTEM.

Application filed August 24, 1922. Serial No. 583,977.

This invention relates to a combined evaporator and feed water system for supplying pure boiler feed in steam generating plants.

Where steam power is generated in quantity as for example where large steam engines are used, the condensed steam from the engines is ordinarily returned to the boiler, the boilers and engines forming a closed circuit in which the water is repeatedly used. There are, however, losses in this water incidental to the operation of the plant caused by leakage, by the use of steam for running auxiliary apparatus of such a character that this steam cannot be entirely returned to the system, and by the use of steam for heating water for industrial use. This loss is made up by the distillation of "raw" water in order to prevent scale-forming or injurious impurities from being carried into the boilers.

This additional or "makeup" water is usually supplied to the boiler feed by evaporators which are heated by steam from the main boilers, and if the quantity of water to be made up reaches more than a small percentage of the boiler capacity the heat losses incidental to vaporizing such a quantity of water will materially reduce the efficiency of the power plant as a whole unless proper provision is made to return to the boilers the heat diverted to the evaporator system.

It has heretofore been proposed to condense the vapor from the evaporators in the main feed water heater for the boiler feed, thereby conserving the latent heat of vaporization, but in power plants utilizing high pressure steam and high pressure evaporators the condensed vapor from the evaporators and the condensed steam from the evaporator coils are at high temperature and hence contain a large quantity of sensible heat which, if wasted, materially lowers the efficiency of the plant as a whole. To avoid this it has been proposed to deliver all the condensed vapor and steam from the evaporator and its coils and from other apparatus from which the exhaust is returnable, along with the condensed steam from the engines to a common "open heater" where the heat from the high pressure apparatus as well as the auxiliary exhaust steam is absorbed by the condensate from the main engines which is at a lower temperature. In some instances this arrangement is satis-

factory, however, the so-called "open heater", although not open to the atmosphere at all times, is nevertheless maintained at atmospheric pressure and in many installations the temperature resulting from the mixing of the returns from the several apparatuses raises the temperature of the open heater above the atmospheric boiling point, thus causing the water in the open heater to boil and entailing loss of a portion of the heat which should be given up to the boiler feed water.

Generally speaking it is an object of the present invention to provide a combined evaporator and boiler feed system in which the resident heat of the system is efficiently utilized, and at the same time the quantity of heat supplied to the open heater reduced to an amount which may be conveniently absorbed therein.

It is a further object of the invention to provide a system of the above type which is capable of furnishing a large percentage of makeup water without raising the temperature in the open heater above atmospheric boiling point, and which is adapted to efficiently operate under various percentages of makeup and varying conditions of load.

More specifically it is an object of this invention to provide in a system of the above type an additional heat exchanger positioned between the plant open heater and the condenser which accommodates the evaporator vapor output for the purpose of transferring heat to the boiler feed water at a temperature intermediate that of the said condenser and the open heater, whereby the quantity of heat contained in the hot fluid discharged into the open heater is reduced to an amount which can be absorbed without loss.

I have illustrated a preferred embodiment of my invention in the accompanying drawings, in which Fig. 1 is a view largely diagrammatic illustrating a power plant layout embodying my invention.

In Fig. 1 is shown a preferred system embodying my invention which is particularly designed for a plant requiring a relatively large quantity of boiler feed makeup water. A multi-effect evaporator plant is shown in which the shell of each effect is connected with the heating coil of the succeeding effect, the vapor from the last effect being passed to a condenser 21. Drains from the coils

- of the several effects are passed through traps 7 to a common line 8, which line communicates by means of a branch line 19 with line 2 leading from the last effect evaporator. 5 Line 8 being in direct communication with the last evaporator effect is at the same pressure as exists in the shell of this effect, and consequently there will be a certain amount of flash steam available from the coil drains. 10 This flash steam passes through line 19, admitting of regulation by means of the valve 20, to the condenser 21 where it serves as a heating medium for the boiler feed water. The water condensate from the coils 5 does 15 not enter the condenser 21 but is passed through a trap 22, from which it flows together with the condensate from the condenser 21 which is discharged from the trap 23, into the low pressure condenser 10. Condenser 10 is maintained at a pressure slightly 20 above atmospheric and flash derived from hot condensate discharged through traps 22 and 23 is here utilized for heating the boiler feed in the same manner as has been described, the condensate from condenser 10 25 passing to the open heater. The boiler feed water passes in series through the open heater, the condenser 10, and the condenser 21, from whence it is conveyed to the boilers. 30 It is to be understood that, if desired, the condenser 10 may be cut out of service by closing the valve 11, in which case the drains from the system are passed into the open heater by way of the by-pass 9^a around 35 trap 9.
- I have referred to the heat exchanger 10 as a condenser, but it is apparent that this term is not to be construed as referring to a specific type of heat exchanger, but that any 40 well known type of apparatus may be employed which is designed to effect an exchange of heat between two fluid mediums.
- While I have illustrated a preferred embodiment of my invention various changes 45 may be made in the arrangement of the parts of the system and the invention is not restricted to any particular type of evaporators, condensers, or the like. Various

changes may be made within the full scope of the appended claims.

50

I claim:

1. In a combined multi-effect evaporator and boiler feed system, means for joining the drains from all the evaporator coils at substantially the pressure existing in the shell of the last effect evaporator, means for conveying the resulting flash steam from said drains together with vapor from the said evaporator shell to a condenser, said condenser being adapted to receive said joined vapors and transfer heat therefrom to the boiler feed water, means for joining the condensate from said coils with the condensate from said condenser at a pressure lower than that maintained in said condenser, a second condenser operating at said lower pressure for receiving said condensate and bringing it into heat exchanging relation with the boiler feed water at said lower pressure, and means for conveying the condensate from said second condenser to the primary boiler feed heater, said boiler feed water passing successively through the primary heater, the second condenser and the first condenser. 65

2. In a combined multi-effect evaporator and boiler feed heating system, means for conveying the vapor from an evaporator shell to a condenser, said condenser being adapted to receive said vapor and transfer heat therefrom to the boiler feed water, means for joining the condensate from the evaporator coils with the condensate from said condenser, a second condenser operating at a lower pressure than that maintained in said first mentioned condenser for receiving said condensate and bringing it into heat exchanging relation with the boiler feed water at said lower pressure, and means for conveying the condensate from said second condenser to a primary boiler feed heater, said boiler feed water passing successively through the primary heater, said second condenser, and said first condenser. 80
